BLACK-OUT VENTILATOR

Walter W. Carver, Millburn, N. J.

Application March 30, 1943, Serial No. 481,169

6 Claims.

(Cl. 98—37)

This invention relates to a device for insertion into an opening such as the port-hole of a ship and when in place it serves to prevent the passage of light as in the precautions taken by shipping in war times.

The invention also relates to a black-out device which serves as a ventilator, allowing a free passage of air and is capable of adjustment for controlling the direction of flow of air through the ventilator.

A further object of the invention is to control the amount of air allowed to pass through the ventilator, this being done by means of a damper which may also include a screen which is over the air passage when the damper is open or partly open.

The device is designed to be made at a reasonable cost and is simple in order to make its manipulation easy.

The invention is illustrated in the accompanying drawing, in which Figure 1 is a central horizontal section of a ventilator made according to my invention. Figure 2 is a face view of the device shown in Figure 1 with the wind scoop partly broken away to disclose the damper and screen.

In the drawing the part 10 represents a ship's plates and 11 is the bolt used to fasten the device in place although other means of fastening the device in place may be used, or the device may be part of the permanent construction of the ship. It is preferably made, however, as a portable ventilator easily attached in the usual form of port-hole by means such as the bolts 11 which are the usual and standard form of fastening.

The device comprises a casing 12 fitting the port-hole. The casing comprises two duplicate rings placed face-to-face and having exterior flanges 13 which are welded together and form a stiffening flange and also a stop for engaging the port light frame 14. The casing has inwardly turned flanges 15 which serve as means for confining a unit inside the casing. The unit may be rotatable inside the casing or fixed therein, as will be described hereinafter.

The unit comprises a cylindrical shell, two semi-circular discs forming the end-walls inclined deflector plates, and wind scoops.

The shell consists of a sheet metal circular band 16 fitting into the casing 12 and held against lateral movement by the flanges 15. The shell has two end walls formed by the outer plates 17 welded to the flanges 16^a of the band 16. The outside plates 17 are arranged on opposite sides of the center, are each substantially

slightly larger than a half-circle and thus extend beyond the center line of the shell leaving the spaces 18 in each side wall of the unit and diagonally opposite. These passages on opposite sides of the center are substantially half the area of each end wall with a straight edge across the center or approximately so and a rounded edge near the edge of the shell.

The inside of the unit is provided with deflector plates that are inclined in a manner to conduct air diagonally through the shell from one opening 18 to the other. The deflector plates 19 are on opposite sides of the center of the shell and each extends from the straight edge of one opening in an end wall to the outer curved edge of the opening in the opposite wall. The edges of the inclined deflector plates may be provided with flanges 20 at the edges, which edges are cut to a shape to fit the curved wall of the shell 16. The flanges 20 are welded to the shell and form a firm and light-proof joint between the deflector plates and the shell.

If desired a central deflector plate 21 is placed equidistant from the end deflector plates 19 and has the flanges 22 for welding it to the shell 16. The abutting edges of the central plate are curved to fit the inside of the shell and the flanges form light-proof joints with the shell.

The unit is provided with a wind scoop and if desired both faces may have such scoop. The scoops 23 are quatri-spherical, conforming on one edge to the shape of the opening and having flanges 24 welded to the flanges 16^a of the shell 16. The scoops have their open ends 25 extended beyond the center of the shell and thus aid in assuring that no light passes through the device.

It will be evident that when the device is inserted in a port-hole, the slotted lugs 26 on the casing receiving the bolts 11 in the usual manner employed on shipboard, the outside scoop will receive air from the direction of arrow a. The air passes into the shell from the scoop and is directed by the deflector plates across the shell and to the other air passage and then out into the inside of the ship. The scoop on the inside face deflects the air and also aids in insuring that light is not permitted to pass through the device. The surfaces of the shell and the deflector plates where they are apt to receive light are treated to make them non-reflecting or light absorbent. This is usually done by giving them a dull black coating.

It will be obvious that if the device is used with the current of air passing in the direction

opposite to arrow *a* the air will be drawn out of the inside of the ship and thus exhausted.

If the current of air is in a direction opposite to the arrow *a* either through a change of wind direction when at anchor or due to the direction of movement of the ship the device is reversed by loosening the fastenings *11*, turning the device a half revolution and again fastening it in place. This places the outside scoop in position for receiving air as before.

In lieu of this the shell *16* may be made so that it may rotate in the casing *12*, and as it carries the deflector plates and the scoops it may be turned a half-turn to suit the circumstances. For more stability, however, the shell *16* is usually welded to the casing *12* and the whole device turned in case it is necessary.

The device may be provided with a damper and screen on its inner wall. The damper is a circular disc *27* with a semi-circular cut-out portion to form the opening *28* of the same general shape and dimensions of the air passages *18*. The disc is provided with a screen *29* over the opening *28*. The disc is pivoted at its center on the bolt or pin *30* and is rotatable. The handle *31* illustrates one means for turning the damper. When the air is to be shut off the damper is turned to place the solid part over the opening *18* on the inner wall of the shell, otherwise the disc can be turned to uncover the opening to any desired extent or it can be fully uncovered. The screen *29* serves to cover the opening *18* when the disc or damper is turned to open part or all of the opening and serves to keep out insects.

It will be observed from the drawing that the open ends of the scoops overlap or extend beyond the center of the device from opposite sides and that the deflector plates overlap, these arrangements insuring the black-out effectiveness of the device.

The capacity of the ventilator is large because most of the area of the inside of the device is available for the passage of air and the air is not impeded by any sharp changes of direction. The inclined, substantially parallel deflectors contribute to the maximum capacity for air.

The deflector plates are arranged diagonally across the shell from one air opening to the other, these air passages being arranged on opposite sides of the center. This contributes to the air capacity but also lends stiffness and bracing. The latter quality is valuable in maintaining the device under the stress of normal travel at sea but also under excess strains due to explosive blast from outside the ship.

It will be evident that various changes can be made in the form and proportion of parts without departing from the scope of the claims.

I claim:

1. A black-out ventilator comprising a hollow casing of cylindrical form having end walls, one of said walls having a semi-circular opening on one side of the central plane passing through the end walls, and the other wall having a similar opening on the opposite side of the plane, each opening being substantially half the area of the wall, inclined deflector plates forming air passages from one opening to the other opening, and wind scoops of quadri-spherical form over each opening and facing in opposite directions.

2. A black-out ventilator comprising a hollow

casing of cylindrical form having end walls, one of said walls having a semi-circular opening on one side of the central plane passing through the end walls, and the other wall having a similar opening on the opposite side of the plane, each opening being substantially half the area of the wall, inclined deflector plates forming air passages from one opening to the other opening, wind scoops of quadri-spherical form over each opening and facing in opposite directions, the inner ends of the scoops extending beyond the center of the casing.

3. A black-out ventilator comprising a hollow casing of cylindrical form having end walls, one of said walls having a semi-circular opening on one side of the central plane passing through the end walls, and the other wall having a similar opening on the opposite side of the plane, each opening being substantially half the area of the wall, inclined deflector plates forming air passages from one opening to the other opening, wind scoops of quadri-spherical form over each opening and facing in opposite directions, a disc rotatably secured to one of the walls to form a damper and having a screened opening to cover the air passage when the damper is open.

4. A black-out ventilator comprising a hollow cylindrical casing, inner and outer walls on the casing, one of said walls having a semi-circular opening on one side of the central plane passing through the end walls, and the other wall having a similar opening on the opposite side of the plane, each opening being substantially half the area of the wall, inclined deflector plates extending from the rounded edge of the opening in one wall to the straight edge of the opening in the other wall, wind scoops of quadri-spherical form on the outside of the walls and over the openings and with their open ends extending beyond the center of the casing.

5. A black-out ventilator comprising a cylindrical casing including a shell having flat end walls, one of said walls having a semi-circular opening on one side of the central plane passing through the end walls, and the other wall having a similar opening on the opposite side of the plane, each opening having substantially half the area of the wall, deflector plates arranged diagonally to conduct air from one opening to the other opening, a central inclined deflector plate between the first mentioned plates, and wind scoops over the openings and arranged with their open ends beyond the center of the casing, the scoops facing in opposite directions.

6. A black-out ventilator comprising a cylindrical casing including a shell having flat end walls, one of said walls having a semi-circular opening on one side of the central plane passing through the end walls, and the other wall having a similar opening on the opposite side of the plane, each opening being substantially half the area of the wall, deflector plates arranged diagonally to conduct air from one opening to the other opening, a centrally disposed inclined deflector plate between the first-mentioned plates, wind scoops over the openings and arranged with their open ends beyond the center of the casing, and a damper rotatable on the inner end wall of the casing, the damper having a screened opening of a size to cover the opening in the inner wall when the damper is open.

WALTER W. CARVER.
